UNITED STATES PATENT OFFICE.

FRANK H. LANGMUIR, OF WOODBURY, NEW JERSEY, ASSIGNOR TO THE BELBER TRUNK & BAG COMPANY, OF PHILADELPHIA, PENNSYLVANIA, A CORPORATION OF PENNSYLVANIA.

DESIGN FOR A TRUNK CORNER PIECE.

Application filed December 24, 1925. Serial No. 15,841. Term of patent 14 years.

To all whom it may concern:

Be it known that I, FRANK H. LANGMUIR, a subject of the King of Great Britain, residing in Woodbury, county of Gloucester, State of New Jersey, have invented a new, original, and ornamental Design for Trunk Corner Pieces, of which the following is a specification, reference being had to the accompanying drawing, which forms a part thereof.

The figure is a perspective view of a trunk corner piece showing my new design.

I claim—

The ornamental design for a trunk corner piece, as shown.

FRANK H. LANGMUIR.
